UNITED STATES PATENT OFFICE.

LORING L. BLAKE, OF CHICAGO, ILLINOIS, ASSIGNOR TO BLAKE PENCIL CO., OF CHICAGO, ILLINOIS, A CORPORATION OF ILLINOIS.

LEAD-FEEDING PENCIL.

1,388,693.

Specification of Letters Patent. Patented Aug. 23, 1921.

Application filed June 26, 1920. Serial No. 391,970.

To all whom it may concern:

Be it known that I, LORING L. BLAKE, citizen of the United States, residing at Chicago, in the county of Cook and State of Illinois, have invented certain new and useful Improvements in a Lead-Feeding Pencil; and I do hereby declare the following to be a full, clear, and exact description of the invention, such as will enable others skilled in the art to which it appertains to make and use the same.

My invention relates to pencils having replaceable leads, and in one of its general aspects aims to provide a simple, and easily manipulated construction which will readily permit the lead to be moved backward or forward with respect to the casing of the holder, and which can be used with leads varying somewhat in size without danger of clogging. 20 In another aspect, my invention aims to provide a lead-feeding pencil so constructed that the portion gripping the lead, as well as some of the parts associated with this portion, can easily be withdrawn entirely from 25 the casing to permit an inspection of the parts and overcome clogging in case a lead should be broken in the holder. For this purpose, it aims to provide a construction in which the actuating part of the pencil-feeding 30 mechanism can readily be moved out of its normally latched position, but in which the auxiliary means prevent an unduly speedy withdrawal of this part of the mechanism when thus unlatched. Furthermore, my in- 35 vention aims to provide an unusually simple, cheap and effective construction of parts for the above purposes, and particularly aims to provide a single member which will simultaneously guide the pencil-feeding screw, 40 prevent the lead-holder proper from rotating, and latch the said screw as well as the handle of the pencil normally in position. It also aims to provide auxiliary means for 45 deterring the withdrawal of the screw and handle from the casing of the holder when unlatched. Still further and more detailed objects will appear from the following specification and from the accompanying drawings, in which—

50 Figure 1 is a central and longitudinal section through a pencil embodying my invention.

Fig. 2 is a perspective view of the lead holder proper which forms a part of Fig. 1.

55 Fig. 3 is an elevation of the handle mem-

ber which includes the lead-feeding screw and which continuously houses at least a portion of the lead-holder of Fig. 2.

Fig. 4 is a perspective view of the inner tube which guides the screw shank of the handle member, which normally latches the handle member in operative position, and which coöperates with the said screw shank in causing the longitudinal movement of the lead-holder.

65 Fig. 5 is an enlarged end view of the inner tube of Fig. 4, taken from the right hand end of Fig. 4.

In the embodiment of the drawings, the holder of my invention includes a tubular 70 casing or barrel comprising a main cylinder portion 1 and a tapering forward portion 2, the latter having a bore closely approaching the diameter of one of the leads 3 which are to be used with the device. Rigidly secured 75 within this casing or barrel is an inner tube 4 which butts at its forward end into the tapering bore of the tip portion 2 and which is enlarged at its rear end to closely fit the main bore of the barrel 1 so that it can 80 readily be soldered to the latter. This inner tube has a longitudinal slot 5 extending from a point near its forward end up into the tapering portion which joins the main part 85 of this inner tube with the enlarged rear end, thereby affording an opening extending radially outward from the main bore portion of this inner tube as shown in Fig. 4. This radial extension 8 of the slot permits the insertion from the rear end of the barrel of 90 the lead-holder proper, which latter consists of a tube 6 which is desirably slotted for part of its length as shown in Fig. 2 to afford a spring grip for the lead. This lead-holder 6 carries a projecting finger 7 of a 95 size adapted to pass through the extension 8 of the longitudinal slot in the inner tube.

The rear end of the casing or barrel is normally closed by a handle 9 which is connected by a stem 10 with a spiral tubular 100 portion 11, this spiral portion being part of the handle member which normally houses at least a portion of the lead-holder 6. When the parts are assembled, the pin 7 on the lead holder extends radially of the latter between two successive turns of the spiral stem portion 11 of the handle member and projects into the longitudinal slot 5 of the inner tube. Consequently, the walls of this slot 5 engage the pin 7 and prevent the lead- 105 110

holder 6 from being rotated, while the helical formation of the part 11 moves the pin backward or forward longitudinally of the appliance according as the handle member 5 is rotated in one direction or the other about its axis. By moving the handle member in a clockwise direction when viewed from the rear end of the pencil, the lead can therefore be advanced to any desired extent, and a rotation of the handle in the opposite direction, 10 will withdraw the lead so that this can be retracted to any desired extent without touching the lead itself with the hand or any other object.

15 To guide the handle member against accidental withdrawal from the casing during the ordinary manipulation of the pencil, I provide suitable means for latching the handle member in the inner tube, and I pref- 20 erably arrange these means so that they will permit the handle member to be freely rotated in either direction and so that they will allow the handle member to be unlatched for withdrawal from the inner tube 25 when in one particular position. To accomplish this, I am here showing the stem 10 of the handle member as provided with a collar 14 normally disposed forwardly of an inwardly directed finger or lug 12 on the 30 enlarged rear end portion of the inner tube, and am showing the stem as contracted in diameter immediately back of this collar 14, for a length corresponding to that of the lug, so as to afford a groove 15 normally 35 engaged by the lug or finger. The collar 14 on the stem has a portion cut away to correspond in contour to the said lug, so that the collar can be drawn past the lug toward the rear of the pencil when the said recess 40 or cut-away portion is opposite the lug.

In practice, this simple latching provision might make it a little too easy to withdraw the handle member, hence I desirably also provide auxiliary means for deterring the 45 withdrawal of the handle member from the barrel of the pencil after the latter is thus unlatched. For this purpose, I desirably mount within the barrel 1 back of the inner tube a flange 13 having its bore threaded 50 to correspond to a thread on the said collar 14, so that after the handle has been unlatched from the lug 12 it still encounters the flange 13 and must be screwed through the latter before the handle member can be 55 entirely withdrawn from the casing. To permit of this auxiliary latching, I space the flange 13 from the lug 12 by a distance slightly greater than the length of the collar 14, so that the latter can rotate between the 60 flange 13 and the lug until started on its threading through the collar 13. In this way, I guard against an unintentional detaching of the parts, and by equipping the collar 14 and the flange 13 with only a few 65 threads, I do not interfere with the normal

operation of the spiral lead-advancing mechanism of my pencil.

With the parts arranged as described and pictured, it will be evident that the inner tube, although quite simply constructed, 70 serves a number of different purposes without requiring any auxiliary parts or fastenings. With the forward end of the inner tube engaging the tapering bore of the barrel, a fastening of the rear part of this 75 tube to the barrel suffices for holding the tube in axial alinement with the barrel. By using a split lead-holder, I secure the desired firm gripping of the lead without requiring an undue exactness in size of the 80 lead, so that I overcome the difficulties met on this score with some of the pencils now on the market. Moreover, the bore of the tip of the barrel need not fit the lead closely, while resiliency of the spiral stem portion 85 11 (which does not need to fit the inner tube closely) permits of variations in the exact size of the various parts.

In practice, the lug 12 is desirably made by forming an inwardly directed bend or 90 indentation at the extreme rear end of the enlarged portion of this inner tube after the manner shown in Fig. 5. However, while I have thus illustrated and described my invention in a highly desirable embodiment, I do not wish to be limited to the details of the construction and arrangement thus disclosed, since various additions and omissions might obviously be made without departing from the spirit of my invention 95 100 or from the appended claims.

I claim as my invention:

1. In a lead-feeding pencil, a tubular casing, a longitudinally slotted guide tube fast therein, a rotatable handle member having 105 a tubular spiral portion disposed within the slotted part of the guide tube, a lead-holder slidably disposed within the said spiral portion; and means associated with the lead-holder, the slot in the guide tube and the said spiral portion for causing a rotation of the handle member to move the lead-holder longitudinally of the casing and for enabling the lead-holder and the spiral tube to be simultaneously withdrawn from the casing 110 by manipulation of the handle member.

2. In a lead-feeding pencil, a tubular casing, a longitudinally slotted guide tube fast therein, a handle member rotatable in the casing and manually removable from the latter and having a tubular spiral portion disposed within the slotted part of the guide tube, a lead-holder slidably disposed within the said spiral portion; and a guide finger fast on the lead-holder and extending 120 through the gap between convolutions of the spiral portion into the slot in the guide tube, the said finger and spiral co-operating to cause a rotation of the handle member in either direction to move the lead-holder 125 130

longitudinally of the casing and also to enable the lead-holder to be withdrawn from the casing upon removal of the handle member from the casing.

- 5 3. In a lead-feeding pencil, a tubular casing, a guide having its rear portion enlarged in diameter and having a longitudinal slot in its forward portion, a handle member rotatably mounted on the casing and having 10 a tubular spiral portion disposed within the slotted part of the guide tube; a lead-holder slidably disposed within the said spiral portion, and a guide finger fast on the lead-holder and extending through the gap between convolutions of the spiral portion into the slot in the guide tube; the said slot extending into the part of the tube connecting the main portion with the said enlarged portion, thereby affording an opening through 15 which the guide finger can pass when the lead holder is withdrawn from the casing.
4. In a lead-feeding pencil, a tubular casing, a lead-holder movable therein, a handle member rotatable on the casing, means associated with the handle member and the lead-holder for causing a rotation of the former to move the lead-holder longitudinally of the casing, and a plurality of means for latching the handle member in the casing, 20 the said latching means being arranged for releasing the handle member from the casing after a plurality of successive rotational movements of the handle member with respect to the casing.
- 35 5. In a lead-feeding pencil, a tubular casing, a lead-holder movable therein, a handle member rotatable on the casing, means associated with the handle member and the lead-holder for causing a rotation of the former 40 to move the lead holder longitudinally of the casing, and a plurality of means for latching the handle member in the casing, the said latching means being arranged for releasing the handle member from the casing after 45 a plurality of successive rotational and longitudinal movements of the handle member with respect to the casing.
6. In a lead-feeding pencil, a tubular casing, a lead-holder movable therein, a handle 50 member rotatable on the casing, means associated with the handle member and the lead-holder for causing a rotation of the former to move the lead-holder longitudinally of the casing, and a plurality of means for 55 latching the handle member in the casing, the said latching means being arranged for releasing the handle member from the casing after a plurality of successive rotational movements of the handle member with respect to the casing.
- 60 7. In a lead-feeding pencil, a tubular casing, a lead-holder movable therein, a handle member rotatable on the casing, means associated with the handle member and the lead-holder for causing a rotation of the former to move the lead-holder longitudinally of the casing, and a plurality of means for latching the handle member in the casing; the said latching means being arranged for releasing the handle member from the casing after a plurality of successive rotational movements of the handle member with respect to the casing.

65 8. In a lead-feeding pencil, a tubular casing, a lead-holder movable therein, a handle member rotatable on the casing, means associated with the handle member and the lead-holder for causing a rotation of the former to move the lead holder longitudinally of the casing, and a plurality of means for latching the handle member in the casing; the said latching means being arranged for releasing the handle member from the casing after a plurality of successive rotational movements of the handle member with respect to the casing, the handle member having a collar equipped with a lateral recess and the latching means including an inwardly directed finger fast with respect to the casing and adapted to pass by the said collar when the recess in the latter is in alinement with the finger.

80 9. In a lead-feeding pencil, a tubular casing, a lead-holder movable therein, a handle member rotatable on the casing, means associated with the handle member and the lead-holder for causing a rotation of the former to move the lead-holder longitudinally of the casing, and a plurality of means for latching the handle member in the casing, the said latching means being arranged for releasing the handle member from the casing after a plurality of successive rotational movements of the handle member with respect to the casing, the handle member having a threaded collar equipped with a lateral recess; the latching means including an inwardly projecting finger fast with respect to the casing and adapted to pass by the said shoulder when the recess in the latter is in alinement with the finger, and a flange fast within the casing back of the finger and threaded to match the threading on the collar.

85 10. A pencil as per claim 7, in which the handle member has a groove back of the collar on the stem corresponding in length to the said finger and normally entered by the tip of the finger, whereby the engagement of the finger with the ends of this groove normally prevents longitudinal movement of the handle member in either direction with respect to the casing.

90 11. In a lead-feeding pencil, a tubular casing, a rearwardly open guide extending longitudinally of the casing within the latter, a handle member rotatably mounted on the casing and having a tubular spiral portion extending adjacent to the said guide, a lead-holder slidably disposed within the said spiral portion and prevented from rotation by engagement with the guide, the handle member being mounted to permit its withdrawal from the casing and the rearward opening of the guide permitting the lead-holder to be withdrawn with the handle member.

115 12. Signed at Chicago, Illinois, June 21, 1920.

120 LORING L. BLAKE.
